UNITED STATES PATENT OFFICE.

FRANCIS WINANS GIBSON, OF WEST ROXBURY, MASSACHUSETTS, ASSIGNOR TO H. D. BEACH COMPANY, OF COSHOCOTON, OHIO, A CORPORATION OF OHIO.

DISPLAY DEVICE.

Application filed May 12, 1924. Serial No. 712,607.

To all whom it may concern:

Be it known that I, FRANCIS W. GIBSON, a citizen of the United States, residing at West Roxbury, county of Suffolk, Commonwealth of Massachusetts, have invented certain new and useful Improvements in Display Devices, of which the following is a specification.

This invention relates to display signs and is particularly intended to display the prices of merchandise on sale. With certain classes of merchandise, the price varies practically from day to day, and hence it is desirable that the sign shall not only be readily legible but that the individual number plates displayed shall be interchangeable so that price fluctuations may be instantly and conveniently indicated. Preferably, such a sign should be mounted in juxtaposition to the goods themselves and should be visible from both directions so as to convey the desired information to the largest number of possible purchasers.

To the end, therefore, of providing a sign which will embody the foregoing desiderata and which at the same time will be simple and inexpensive of manufacture and in which the individual number plates may be conveniently interchanged as occasion demands, I have devised my present invention. According to it, I provide a slotted bracket arm which is formed at one end to accommodate a comparatively wide range of different sizes of mounting supports and at its other end is provided with a slot within which the suspension flanges of two spaced sets of longitudinally alined overlapping number plates may be inserted. This arrangement suspends the two sets of number plates in conveniently legible relation to the goods on sale, and the slot is wide enough and long enough to accommodate two individual sets of number plates arranged in proper relative sequence so that the same set of numerals may be exposed from two opposite directions.

The construction and manner of use of my sign, together with a selected embodiment thereof which well illustrates the principles involved, is described and shown in the accompanying specification and drawings, and the characteristic features of novelty are particularly pointed out in the appended claims. Throughout the specification and drawings, like reference characters

are employed to indicate corresponding parts. In the drawings:

Figs. 1 and 2 are elevations from opposite sides of a sign in accordance with my invention.

Fig. 3 is a plan view thereof.

Fig. 4 is a section on the line 4—4 of Fig. 3.

I have indicated at 1 and 2 a pair of duplicate arms which are bent at their outer ends to provide a slot 3 of the desired width and length and are riveted or otherwise secured together at the extremities of said slot as indicated at 4. At their inner ends the arms 1 and 2 are bent into substantially V-shape so as to define a generally rectangular opening 5 for the reception of a mounting support S to which said arms may be bolted as indicated at 6.

The number plates 7 are duplicate in construction, and each consists of a flat display panel from the upper end of which depends a supporting flange 8 adapted to enter the slot 3 defined by the arms of the bracket. The lower edge of each plate is preferably upturned as indicated at 9 to provide a smooth rounded edge.

In the form of my invention shown in the drawings, the slot 3 is of a length and width sufficient to accommodate two pairs of number plates, one pair at each side of the bracket arm. In use the four number plates bearing the desired set of numerals are mounted on the bracket arm in their proper relative sequence by inserting their suspension flanges 8 in the slot 3. This positions the number plates as two reversely arranged sets displaying the same numerals from opposite sides of the bracket arm, the suspension flanges of the individual plates bearing against each other and serving to anchor the plates against relative movement in the slot and the adjacent vertical edges of each set of plates slightly overlapping each other so as to give the effect of a continuous flange at the bottom edges of the plates.

Various modifications in the form and construction of my device may obviously be resorted to without departing from the spirit of my invention if within the limits of the appended claims.

What I therefore claim and desire to secure by Letters Patent is:

1. A price sign comprising a bracket hav-

- ing a mounting clamp and having a longitudinally disposed slot beyond said clamp, and reversely arranged sets of juxtaposed legend bearing plates having each a suspension flange bent downwardly from its upper edge and inserted in said slot of the bracket and concealing both faces of the bracket included by said plates, the plates of one set being spaced apart from the plates of the other set by the thickness of the intervening arms of the bracket and all plates in each set being disposed in longitudinal alignment with each other longitudinally of the bracket so as to present the effect of a continuous one-piece plate when viewed from either side of the bracket. 25
10. of the other set by the thickness of the intervening walls of the slot and all plates in each set being disposed in longitudinal alignment with each other longitudinally of the bracket so as to present the effect of a continuous one-piece plate when viewed from either side of the bracket. 30
15. continuous one-piece plate when viewed from either side of the bracket. 35
2. A price sign, comprising a pair of bracket arms bent at one end to provide a mounting clamp, and beyond said clamp spaced apart from each other to define a continuous longitudinally extending slot,

and reversely arranged sets of juxtaposed legend bearing plates, having each a suspension flange bent downwardly from its upper edge and inserted in said slot of the bracket and concealing both faces of the bracket included by said plates, the plates of one set being spaced apart from the plates of the other set by the thickness of the intervening arms of the bracket and all plates in each set being disposed in longitudinal alignment with each other longitudinally of the bracket so as to present the effect of a continuous one-piece plate when viewed from either side of the bracket.

In testimony whereof I affix my signature in presence of two witnesses.

FRANCIS WINANS GIBSON.
